CLAIM

The ornamental design for a pedicure spa, as shown and described.

DESCRIPTION

FIG. 1 is a perspective view showing the front, left and top of a pedicure spa showing my new design; the broken lines shown in the drawings represent unclaimed portions of the design.

FIG. 2 is a rear view of the pedicure spa, such as that shown in FIG. 1;

FIG. 3 is a front view of the pedicure spa, such as that shown in FIG. 1;

FIG. 4 is a left side view of the pedicure spa, such as that shown in FIG. 1;

FIG. 5 is a right side view of the pedicure spa, such as that shown in FIG. 1;

FIG. 6 is a front view of the pedicure spa, such as that shown in FIG. 1, without a chair mounted on the pedicure spa;

FIG. 7 is a rear view of the pedicure spa, such as that shown in FIG. 1, without a chair mounted on the pedicure spa;

FIG. 8 is a top view of the pedicure spa, such as that shown in FIG. 1; and,

FIG. 9 is a left side view of the pedicure spa, such as that shown in FIG. 1, without a chair mounted on the pedicure spa.
